UNITED STATES PATENT OFFICE.

CHESTER W. METZGAR, OF EASTON, PENNSYLVANIA, ASSIGNOR TO INGERSOLL-RAND COMPANY, OF JERSEY CITY, NEW JERSEY, A CORPORATION OF NEW JERSEY.

COMPRESSOR REGULATOR AND UNLOADER.

Application filed November 3, 1925. Serial No. 66,492.

This invention relates to compressors, but more particularly to a regulator and unloader.

One object of the invention is to secure an efficient regulator and unloader for an installation in which there is another unit or prime mover in addition to the compressor, as for instance a mine hoist, which operates intermittently. In such installations, in which both the compressor and hoist are electrically driven, the cost of current is frequently computed according to the peak load for the day, regardless of whether current is used continuously or not and if the compressor is running and the hoist is started up, the peak load is excessively high. An object of this invention is therefore to keep the maximum demand charge as low as possible by means of the regulating and unloading apparatus.

Another object is to enable the compressor to be started and stopped from the main switch board of the plant, by distant control, which includes control of an auxiliary automatic device which may be an electro-responsive unloader for permitting the compressor to run unloaded while the hoist is running, thus avoiding excessive peak loads.

A further object is to secure complete unloading by means of a by-pass connection on each cylinder of a multi-cylinder compressor as a duplex or a multi-stage compressor, which provides a sixth step of unloading on a five step control and also constitutes an efficient start and stop unloader capable of being controlled from the main switch board.

The invention is shown in one of its preferred forms in the accompanying drawings in which,

Figure 1 is a diagrammatic representation of a power plant showing an electrically driven compressor and a second electrically driven power unit, in the form of a mine hoist, both controlled from a common main switch board,

Figure 2 is an enlarged detail side elevation partly in longitudinal section through the electro-responsive auxiliary device of the regulator and unloader for the compressor,

Figure 3 is a diagrammatic view of a duplex compressor partly in sectional plan view having the regulator assembled therewith,

Figure 4 is an enlarged detail sectional elevation of the pressure responsive regulator and unloader taken on the line 4-4 of Figure 5 looking in the direction of the arrows. In this view the parts have been shown in one plane for better illustration and to show the various ports, passages and valves, and

Figure 5 is a horizontal sectional view of the regulator on the line 5-5 of Figure 4 looking in the direction of the arrows.

Referring to the drawings, the installation shown diagrammatically in Figure 1 comprises the compressor having the cylinders A and B in this instance a duplex compressor being shown adapted to be connected in the usual manner to the discharge tank or receiver C, the intake and discharge connections of the compressor being omitted for simplicity of illustration. The discharge outlets of the cylinders are indicated at D and E, and the cylinders are provided with the usual pistons F and the inlet and discharge valves G and H. The compressor is electrically driven by means of the motor J supplied with current from the mains K and leads L carried by the main switch board O on which the compressor switch P is mounted.

In the present instance, a second power unit is adapted to operate in conjunction with the compressor and is shown as a mine hoist Q having the drum R driven by the electric motor S and having a starting box T from which the leads U connect to the hoist switch V on the main switch board O. A volt meter W is preferably included in the circuits for indicating purposes.

The compressor is provided with a pressure responsive regulator and unloader X actuated in this instance by receiver pressure from the pipe a connecting the receiver C to the point b on the regulator casing and communicating with the diaphragm chamber c having the diaphragm d operatively connected to actuate the weighted lever e in accordance with variations in the receiver pressure.

The regulator X is constructed similarly to and operates like the compressor regulator disclosed in Patent No. 1,430,578 granted to me October 3, 1922, with the exception, that in accordance with the present invention, I have added a sixth step to the regu-

lator effected by the main operating valve in the auxiliary casing Y which causes the actuation of the unloader valves *f* controlling the by-pass connections *g* between the ends of the cylinders A and B. In this instance, the system of unloading is like that indicated in my former patent in which the cylinders are provided with the clearance chambers *h* controlled by the clearance valves *j* operating in the valve casings *k* adapted to be connected by the pipes 1, 2, 3 and 4 with the correspondingly numbered pipes 1, 2, 3 and 4 on the regulator X. The auxiliary casing Y for the sixth step of unloading is connected by a pipe 5 to the unloader casings *o* of the by-pass valves *f*.

All the unloader valves and by-pass valves are adapted to be held closed by a receiver pressure in the usual manner and they are assisted in opening by springs (not shown) when pressure is released from the valves successively. In operation as usual the pairs of valves 1, 2, 3 and 4 are operated successively for loading and unloading, but in the present instance, the four by-pass valves *f* are all operated together as the last or sixth step of unloading for a purpose to be described which differs in operation from the by-pass valve shown in my former Patent No. 1,430,577 for a fluid compressor, granted October 3, 1922, inasmuch as the present by-pass valves are operated as a separate step of unloading while in said former patent, by-pass valves were operated as the fifth step of unloading in conjunction with the last two clearance chamber valves. In referring to the number of steps of unloading as five step or six step as the case may be, it is to be understood that full load constitutes the first position of the valves and may be considered the starting point of unloading and if the remaining steps comprise three-quarter load, one-half load, one-quarter load and no load, the regulation is regarded as five step control. In accordance with the present invention six step control is effected comprising full load, three-quarter load, one-half load, one-quarter load, no load, with all the clearance valves open but the by-pass valves closed and the last or sixth step of complete unloading effected by opening all the by-pass valves and connecting pairs of clearance chambers between the ends of the cylinders. This last step is specially advantageous because it may be availed of in connection with the regulation and may be manually controlled as a start and stop unloader.

In accordance with the present invention, an adjunct or auxiliary automatic device *Z* is provided in conjunction with the main regulator and unloader X and cooperating therewith, but manually controlled at a distance as by means of the switch *p* from the main switch board O for the purpose of actuating the lever *e* of the regulator and

partially or completely unloading the compressor at any desired time, regardless of the automatic control of the regulator.

The auxiliary device *Z* is preferably electro-responsively controlled by means of the solenoid *q* indicated diagrammatically in the drawings and connected by the leads *r* to the switch *p* on the switch board. The auxiliary device *Z* may be constructed in any suitable manner for the purposes indicated, but in this instance comprises the pressure cylinder *s* having the piston *t* provided with the stem *u* extending through the stuffing box *v* and having the adjustable tip *w* bearing under the outer end of the lever *e*. The supply and release of receiver pressure fluid for the cylinder *s*, supplied by the pipe *x* and released through the atmospheric port *y*, is controlled by the solenoid *q*, and operative connections between the armature *z* of the solenoid and the inlet and release valves 6 and 7 are indicated below the lower head 8 of the cylinder *s*. When the piston or plunger *t* of the auxiliary device *Z* is moved upwardly by pressure, the weighted lever *e* of the main regulator is raised either partially or fully depending upon the adjustment of the set screw or stop 9 to either partially or fully unload the compressor while running or to completely unload the compressor when starting or stopping. As the pressure beneath the auxiliary plunger *t* is released, the weighted lever *e* falls and the main regulator *Z* resumes automatic operation.

By manipulation of the auxiliary device *Z* from the switch board O, excessive peak loads for the apparatus may be avoided, because if it is desired to start the hoist Q while the compressor is running under load, the solenoid switch *p* is first opened which deenergizes the solenoid *q*, supplies pressure fluid to the plunger *t* of the device *Z* and causes the stem *u* of the plunger to raise the weighted lever *e* which unloads the compressor. The hoist switch V on the switch board may then be closed to start the hoist motor S and the compressor may run unloaded or partially unloaded while the hoist is running. This operation avoids the greatest peak loads usually due to the starting of the hoist motor and also due to conjoint operation of both the compressor motor and the hoist motor fully loaded.

In order to indicate to the switch board tender that the auxiliary device *Z* has caused the unloading of the compressor, a signal light 10 on the switch board is connected by the connections 11 to a switch 12 mounted adjacent the auxiliary device *Z* and having a finger 13 adapted to be actuated by a member 14 to close and open the switch 12 as the plunger *t* moves upwardly and downwardly. The member 14 is carried by the stem 15 guided in the frame of the de-

vice Z and normally held in retracted position by the spring 16. The end 17 of the stem 15 forms a stop and a set screw 18 forms another stop for actuating the tongue 5 or finger 13 of the switch. The arm 19 has a rod 20 suitably secured thereto and extending through the guide sleeve 21 on the auxiliary cylinder 8, so that the rod 20 follows the movement of the plunger *t* and raises 10 and lowers the member 14 to close and open the switch 12 and thus indicate to the switch board tender by means of the signal light 10 whether or not the compressor is unloaded.

15 The valves 6 and 7 for the auxiliary device Z may be in the form of needle valves as shown provided with the valve springs 22 and the stems 23 of the valves are adapted to be alternately actuated by the stops 20 24 carried by the pivoted lever 25, one end 26 of said lever engaging the stirrup 27 connected to the solenoid core *z*. When the solenoid *q* is energized, the lever 25 will be rocked on its pivot 28 to the position shown 25 in Figure 2 in which case the valve 6 will be closed and the release valve 7 will be open and the plunger *t* will be in its lowermost position. Upon deenergizing the solenoid *q*, the solenoid core *z* falls and the position of 30 the valves 6 and 7 is reversed so that pressure fluid from the receiver actuates the plunger *t* upwardly as hereinbefore described. The upper portion of the cylinder 8 is preferably vented to atmosphere through 35 the atmospheric vent 29.

The construction and operation of the main regulator X with the exception of the additional main operating valve in the casing Y is fully described and shown in my 40 aforesaid Patent No. 1,430,578 so that this regulator will be but briefly described, reference being had to said patent for further details. The auxiliary or pilot valve 30 of the regulator X is connected at the point 45 31 to the weighted lever *e* and is provided with the heads 32 and 33 operating in the valve chamber 34. The space between the heads 32 and 33 is constantly subjected to receiver pressure through the ports 35 communicating with the pipe 36, subject to receiver pressure. Main operating valves 37 of which there are four, are provided with the heads 38 and 39, and control the pipes 1, 2, 3 and 4 leading to the clearance valve 50 casings *k*. The fifth main operating valve 37 is contained in the valve casing Y and controls the pipes 5 leading to the by-pass valve casings *o*. The main regulator X is provided with the atmospheric vent pipe 40 55 and the auxiliary casing Y of the regulator is provided with the atmospheric vent pipe 41. The shoes 42 of the main operating valves 37 control the ports 43 and 44. The spaces 45 between the valve heads 38 and 39 60 are constantly open to receiver pressure

through the passages 46, and ports 1^a, 2^a, 3^a, and 4^a controlled by the head 32 of the auxiliary valve 30, alternately supply pressure to and release pressure from the heads 39 of the main valves 37, while ports 1^b, 2^b, 3^b and 4^b function in the same manner for the heads 38 of the valves 37. The passage 47 is open to atmosphere and communicates through appropriate ports and passages with the end faces of the valve heads 38. 75 Obviously, as the shoes 42 of the valves 37 move up and down, pressure is successively supplied from the valve spaces 45 to the pipes 1, 2, 3 and 4 leading to pairs of clearance valve casings *k* for holding the clearance valves closed and for successively releasing the pressure in said pipes through the ports 43 and 44 and the atmospheric vent 47. The valve 37 in the auxiliary valve casing Y which controls the by-pass valves 80 of the compressor operates in the same manner and is provided with auxiliary passages 48 and 49 leading to the ports 50 and 51 respectively which are also controlled by the valve heads 32 and 33 of the auxiliary valve 85 30. The valve 37 in the casing Y alternately supplies and releases pressure in the pipes 5 for the sixth step of unloading and loading.

1 claim:

1. In an inter-control system, the combination of two power driven devices and pneumatic means for decreasing the power consumption of one of said devices in anticipation of and only during the acceleration period of the other said device. 95

2. In a compressor, the combination of a cylinder and piston, an automatic pressure responsive regulator for unloading and loading the cylinder in successive steps, 105 means for causing the regulator to unload the cylinder through a predetermined number of steps in one operation, a by-pass connection between the ends of the cylinder, the last step of unloading comprising the opening of said by-pass connection, and an auxiliary electro-responsive device manually controlled from a distance cooperating with said regulator for actuating the regulator to complete unloading position at any desired 110 time, whether the compressor is running full speed or starting or stopping.

3. In a compressor, the combination of a cylinder and piston, unloading devices for said cylinder including a by-pass connection between the ends of the cylinder and a by-pass valve, an automatic pressure responsive regulator controlling said unloading devices and the by-pass valve successively, the opening of the by-pass valve constituting the last 120 step of unloading, means for causing the regulator to unload the cylinder through a predetermined number of steps in one operation, and an auxiliary electro-responsive device manually controlled from a distance for 125 130

actuating the regulator to completely unload the compressor through all the steps at any desired time.

4. In a compressor, the combination of a cylinder and piston, an automatic pressure responsive regulator for unloading and loading the compressor in successive steps, an auxiliary cylinder and pressure actuated piston for causing the regulator to unload the cylinder through a predetermined number of steps in one operation, and electro-responsive means for controlling said auxiliary cylinder and piston, in turn manually controlled from a distance, whereby the compressor may be unloaded as desired.

5. In a compressor, the combination of a cylinder and piston, an automatic pressure responsive regulator for unloading and loading the cylinder in successive steps, an auxiliary cylinder and pressure actuated piston for causing the regulator to unload the cylinder through a predetermined number of steps in one operation, and electro-responsive means for controlling said auxiliary cylinder

and piston, in turn manually controlled from a distance, whereby the compressor may be unloaded and loaded at any desired intervals, regardless of the automatic action of the regulator.

6. In an apparatus of the class described, the combination of an electrically driven compressor and a second electrically driven power unit adapted to be operated intermittently, a main switch board and switches for the motors of the compressor and second unit, a pressure responsive regulator for unloading the compressor, an auxiliary electro-responsive device for causing the regulator to unload the compressor at will, and a controlling switch on the switch board for said auxiliary device, whereby the compressor may be unloaded while running to permit the second power unit to be started and thus avoid excessive peak loads.

In testimony whereof I have signed this specification.

CHESTER W. METZGAR.
